UNITED STATES PATENT OFFICE.

EMIL PIEPENBRING, OF DORTMUND, GERMANY.

MINER'S SAFETY-LAMP.

No. 846,050.

Specification of Letters Patent.

Patented March 5, 1907.

Application filed June 22, 1905. Serial No. 266,380.

To all whom it may concern:

Be it known that I, EMIL PIEPENBRING, a citizen of the German Empire, and a resident of Dortmund, Germany, have invented certain new and useful Improvements in and Relating to Miners' Safety-Lamps, of which the following is a specification.

Ordinary miners' safety-lamps present one or more perforations in the lamp-reservoir, serving partly for regulating the height of the flame and partly for kindling it, whether the ignition is effected by striking or frictional means. These perforations in the lamp-reservoir give rise to numerous leakages; further, the independence of the regulation of the burner from the ignition is inconvenient in practice, as it is always necessary in the first place to bring the wick into position suitable for kindling before this operation can be effected.

The present invention obviates both these defects by the employment of a lamp-reservoir in one piece, by the rotation of which relatively to an outer protecting-envelop both the regulation of the burner and the kindling of the lamp are effected, and by means of this device both operations are rendered interdependent in the manner required by considerations of safety.

The novel lamp is illustrated in Figures 1 to 7 of the accompanying drawings. Fig. 1 shows the lamp in section in the position for kindling. Fig. 2 is a diagrammatic view of the operating parts illustrated in Fig. 1, showing them laid out in a plane. Fig. 3 is a section through the lamp when ready for taking apart. Fig. 4 is a diagrammatic view of the operating parts illustrated in Fig. 3, showing them rolled out in a plane. Fig. 5 is a partial section through the lamp drawn to a larger scale for the purpose of illustrating the arrangement of the operating mechanism. Fig. 6 is a section through the upper part of the protecting-envelop after the lamp-reservoir has been taken out, showing the locking mechanism fastened. Fig. 7 is a similar section showing the locking mechanism unfastened by magnetic means. Fig. 8 is a perspective view of part of the lamp, showing the igniting-strip and adjoining parts; and Fig. 9 is a plan thereof.

The lamp-body *a*, which is stamped out in a single piece, is only perforated at its upper part by a charging or cleaning aperture 55 which receives the burner-tube *c*, which is soldered into the burner-plate *b*, which also

receives the kindling-tube *d*. Upon the upper part of the lamp-reservoir the kindling device is fixed. It consists of a centrally-arranged guide-ring *e* for the kindling-band *f* and of the igniting-spring *g*, which is mounted in such a manner that the igniting-pellets are caused to explode. An operating-ring *h* is rotated by the stepped portion of the lamp-reservoir *a* by friction and carries the free extremity of the igniting-strip *f*, which is firmly held therein. The outer protecting-envelop, which forms a tight joint with the lamp-reservoir, consists of the cylindrical part or casing *i* and the igniter-cover *k*. This cover *k* carries in its tubular addition *l* a spiral spring *m*, which constantly presses the burner-plate upon its seat, and thereby presses the entire lamp-reservoir downward. The cylindrical part *i* carries upon its inner periphery the igniting and regulating cams or curves *n*, with the safety-fastening, which consists of a flanged ring *p*, freely displaceable in the cylinder *i* and depressed by the springs *o*. This ring *p* carries the bolts *q*, forming the continuation of the igniting-cams.

The lamp is prepared for use and operated in the following manner: The filled lamp-reservoir *a* is inserted in the protecting-casing *i*, being given the necessary centering by its projection *r*. Its guide-studs *s* are brought beneath the bolts *q*, and these latter are pressed upward, so that after slight rotation the studs come upon the ignition-cams *n*. The bolts again snap to under the influence of the springs *o*, so that it is impossible for any unauthorized opening of the lamp to take place. Now if the lamp-reservoir *a* is rotated still further in the same direction relatively to the protecting-casing (in Fig. 2 toward the right hand) its studs *s* will mount the igniting-cams against the pressure of the spring *m*, mounted on the igniter-cover *k*. The burner-tube *c* and the kindling-tube *d* participate in this ascent and reach the kindling position, the burner projecting considerably from the igniter-cover and the kindling-tube coming in front of an appropriate slot *t* in this cover. When the burner has obtained its maximum elevation, one of the pellets of the igniting-strip *f* is exploded, thereby igniting the auxiliary burner, which in turn kindles the main burner. For this purpose the following construction has been devised: Shortly before the studs *s* reach the highest point of the curves the flange of the

operating-ring *h* comes against the friction-plate *u*, which is yieldingly supported and mounted in such a manner as to be incapable of rotation relatively to the protecting-envelop *i*. In order to form a tight joint between the lamp-reservoir and the envelop, this plate *u* is provided with an india-rubber washer *v*. The lower flanged portion of this washer bears around the friction-plate *u* in order that owing to its high coefficient of friction it may insure the retention of the operating-ring by the friction-plate, even with equal pressure between the friction-plate, operating-ring, and lamp-reservoir. If desired, the upper portion of the operating-ring may be roughened. Owing to the pressure exerted by the springs the operating-ring will be held so long as it is within reach of the plate *u*. Relative displacement between the operating-ring *h* and the lamp-reservoir is, however, possible, and as the ring holds one end of the kindling-strip a pellet of this latter is exploded. Now if the duration of the contact between the operating-ring *h* and the friction-plate *u* is appropriately calculated the kindling-strip is displaced by the amount of an interval between the pellets. As a result of this each time the summit of the igniting curves or cams is passed ignition will take place. The kindling-spool is placed in the interior of guide-ring *e*, the free end of the spool passing through a slot of such ring and being clamped to ring *h*. If ring *h* is rotated in the manner described, the kindling-strip is drawn along the outer periphery of ring *e* and across the igniting-spring *g* to effect the explosion of one of the pellets. The spark thus produced will ignite the auxiliary burner *d*, which will in turn ignite the wick in main burner *c*. The regulation of the length of the flame is effected by the elevation of cover *k* by cams *n*, which also in its raised position extinguishes the auxiliary flame by cutting off the air-supply. The lamp may be taken apart for cleaning and replenishing by lifting the magnetic fastening. The small armatures *w*, fixed upon the flanged ring, are lifted by the application of an appropriately-formed magnet against the influence of the

springs *o*, and thereby lift the bolts *q* out of the igniting-curves. By this means the studs *s* are able to descend, and the lamp-reservoir *a* may be withdrawn from the envelop *i*. When assembled, the lamp is protected from any unauthorized opening.

What I claim is—

1. In a safety-lamp, a reservoir, a main burner, an auxiliary burner and an igniter mounted upon the reservoir, combined with a casing adapted to be rotated and reciprocated on the reservoir, an ignition-strip, and means intermediate reservoir and casing for drawing said strip across the igniter, substantially as specified. 65

2. In a safety-lamp, a reservoir, a main burner, an auxiliary burner and an igniter mounted upon the reservoir, combined with a casing adapted to be rotated and reciprocated on the reservoir, a ring inclosed within the casing and loosely mounted upon the reservoir, an ignition-strip secured to the ring, and a friction-plate on the casing adapted to engage the ring, substantially as specified. 70

3. In a safety-lamp, an open reservoir, a top plate carried thereby, a main burner and an auxiliary burner secured to the plate, a ring rotatable on the reservoir, and an ignition-strip secured to the ring, combined with a casing adapted to be rotated and reciprocated on the reservoir, a perforated cover secured to the casing, a spring intermediate plate and cover, and a friction-plate on the casing adapted to engage the ring, substantially as specified. 75

4. In a safety-lamp, a stepped reservoir, a main burner, an auxiliary burner, an igniter and studs secured to the reservoir, a flanged rotatable ring engaging the reservoir-step, an ignition-strip secured to the ring, combined with a casing rotatable on the reservoir, a cam secured to the casing and engaged by the studs, and a friction-plate on the casing adapted to engage the ring, substantially as specified. 90
